Attest,

Geo. E. Miles
J. Osborne,

Inventor,

Joseph H. Barker,
by Leontine,

Attorney.

UNITED STATES PATENT OFFICE.

JOSEPH H. BARKER, OF CINCINNATI, OHIO.

THILL-COUPING.

SPECIFICATION forming part of Letters Patent No. 319,946, dated June 16, 1885.

Application filed August 29, 1883. Renewed January 29, 1885. (No model.)

To all whom it may concern:

Be it known that I, JOSEPH H. BARKER, a citizen of the United States, residing at Cincinnati, Hamilton county, State of Ohio, have 5 invented new and useful Improvements in Thill-Couplings, of which the following is a specification.

My invention relates to thill-couplings for road-vehicles, and is designed to provide an 10 inexpensive and efficient device which can be applied to existing structures for preventing the disagreeable "rattling" due to lost motion in the shaft-connections.

To this end it consists, substantially, in the 15 provision of an adjustable wedge or wedges with adjusting and holding devices, adapted to be inserted behind the pivot-coupling between the jaws of the clip for the purpose of forcing and holding the shaft-loop against its 20 pivot-bolt, as hereinafter more fully described.

Mechanism embodying my invention is illustrated in the accompanying drawings, in which the parts hereinafter described are designated by corresponding letters of reference.

25 Figure 1 of the drawings is a side view of a preferred form of my improved coupling; Fig. 2, a cross-section of the same.

Referring to the drawings in aid of the following description, A is the clip surrounding 30 the axle; B, one of the two projecting jaws, between which the shaft-bolt *b* is inserted for holding the thill C.

In the preferred form of my device, exhibited in Figs. 1 and 2, I use a wedge-shaped 35 block, D, of metal or any suitable material, terminating in or having attached thereto a projecting screw, *d*. This is inserted behind the thill-coupling between the coupling-jaws,

and the screw *d* passed through a rectangular metal washer, *a*, adapted to rest upon the jaws 40 B, behind the thill-coupling, and through a spring-washer, *c*, and is finally provided with a nut, *e*, by which it is held in place and adapted to take up any lost motion due to wear. A convenient form of the spring-washer 45 is that shown, consisting of a perforated cylinder, *c*, of rubber, or a spiral spring, surrounding the screws *d*, protected exteriorly by an open casing, *f*, of metal, and above by an ordinary metal washer fitting loosely within 50 the casing.

The mode of operation is obvious. The nut *e*, acting against the washer *a* as an abutment, draws up the wedge D between the thill-coupling and the clip, and forces the latter outward against its pivot-bolt. The interposed spring-washer *c* acts to take up minute losses of wear, and also enables the wedge D to yield to inequalities in the contour of the thill-loop in the pivotal play of the shafts. 60

I claim as my invention and desire to secure by Letters Patent—

The take-up device for thill-couplings, consisting of the wedge-block D, terminating above in a screw, *d*, the abutment-plate *a*, the 65 spring-washer *c*, and nut *e*, all combined and arranged as shown, and for the purpose specified.

In testimony whereof I have hereunto set my hand in the presence of two subscribing 70 witnesses.

JOSEPH H. BARKER.
